LOOPEP PILE RUG

Burton A. Olsen, Oakland, Calif., assignor to National Automotive Fibres, Inc., Detroit, Mich., a corporation of Delaware

Application August 9, 1949, Serial No. 109,377

2 Claims. (Cl. 2—278)

1

This invention relates to looped pile rugs.

In the general art of rug making, difficulty has always been encountered because of the desire for larger sizes than is possible to weave or manufacture on conventional machinery. Thus, for example, in the conventional looped pile rug, machinery is available which will conveniently form a strip only approximately 36 inches wide. As a consequence, when wider widths are required, it is necessary to join two or more strips. This joining procedure has generally taken the form of a strapped butt joint, in which a strip of material is glued or otherwise secured to the backing sheet along the underside of the abutting edges. Glass or plastic tape has ordinarily been employed for this purpose.

For some types of construction, this has been fairly satisfactory, but in other instances, it produced an unsightly and clearly visible joint. This was particularly true where as in the case of looped pile rugs, the pile or loops were grouped in a series of parallel rows, spaced from one another approximately one fourth of an inch. The best solution in the art was to trim the edges of the backing sheets as close as possible to a line of pile in order that when two strips were brought edge to edge, the pile would tend to overlap and cover up the seam.

The present invention has been designed to overcome these difficulties by leaving a relatively wide marginal portion along one edge of the backing sheet, which strip is without loops or pile. The other edge is conventionally formed with a line of pile secured in the strip as closely as possible to this latter edge, and preferably, this other edge is formed with a shorter pile. Thus, when two strips are brought together, the wide un-looped edge is joined to an edge having the loops closely adjacent. They are joined by positioning the more conventional edge over the marginal portion of the adjoining edge in a lapped joint. A suitable adhesive such as latex is used to secure the same together and after gluing, the same may be passed through pressure rollers to improve the attachment. As a consequence, an excellent joint is produced which can be formed easily and inexpensively.

Thus one of the objects of the present invention is a looped pile rug formed of strips of material which present a uniform appearance on the upper side, the joints being practically invisible.

Another object of the invention is a looped pile rug formed of strips having joints which are essentially invisible from the upper side.

A further object of the invention is a looped

2

pile rug formed of strips in which one edge of each strip containing no pile is used to form a lapping joint with a piled edge of an adjoining strip.

5 Yet another object of the invention is a looped pile rug formed of strips of material utilizing a portion of the backing strip to form a lapped joint.

An even further object of the invention is a 10 looped pile rug formed of strips of material joined together in a lapped joint.

And still another object of the invention is a 15 looped pile rug formed of strips having a marginal portion with shorter pile.

In the drawings:

Fig. 1 is a plan view of a rug illustrating the preferred form of the invention.

Fig. 2 is a partial end view of a rug utilizing the preferred form of the invention, showing in detail the joinder of the strips.

In general, the invention is concerned with a 20 looped pile rug which is exceedingly easy to manufacture and whose seams are substantially invisible.

25 Two factors contribute to this effect. One is obtained by leaving a marginal portion of each strip free of pile, so that another strip of material may be placed in overlapped position on the marginal portion. The other factor is obtained by utilizing a shorter pile on the overlapping portion.

The preferred form of rug is illustrated in the drawings, but it is to be clearly understood that the form shown is illustrative only and other and 30 various forms will be obvious to those skilled in the art.

The preferred form shown comprises a plurality 35 of strips of backing sheet material 1 which may be canvass, duck or any suitable material. Secured to each strip of backing sheet material is a series of rows 2 of pile. The pile is preferably secured to the sheets 1 by forcing one or more strands or tufts 3 of the pile material, which may be wool, cotton, etc., through the sheets so that they extend above the surface thereof a suitable distance. In the example, a looped cotton pile is illustrated and each tuft 3 comprises approximately three strands of cotton material.

In the ordinary case, the thickness of the 40 backing sheets 1 may be of the order of $\frac{1}{64}$ inch and the tufts or loops may be approximately $\frac{1}{2}$ inch long or high, and spaced in rows approximately $\frac{1}{4}$ inch apart.

The description above is applicable to conventional construction. The invention is concerned

55

with a marginal portion 4 along one edge of the strips 1, which, in practice may be of the order of 1-1½ inches wide. As can be seen in Fig. 2, this permits the opposite edge of a similar strip 1 of material to be joined to it in overlapped position. In this position, the several outer rows 2A of pile on the uppermost strip will overlie the marginal portion 4 of the adjacent strip. The edge of the uppermost strip is positioned closely adjacent the row 2B of pile next to the marginal portion on the undermost strip in a manner that the adjacent rows 2 of pile on the adjacent strips are spaced apart a distance approximately equal to the spacing of the rows.

The two strips are joined along this marginal portion by any convenient means. The most feasible is by coating the upper side of the marginal portion 4 with a layer of adhesive, such as latex, and pressing the overlapping portions together. Since the strips are generally very long, this is preferably accomplished by passing the strips longitudinally through a pair of rollers to force the adjacent portions into close contact while the adhesive is permitted to dry or set.

In order to make an even more desirable and less visible joint, it is preferred to form the rows 2A of pile on the overlapping edge of the strip slightly shorter than the remaining rows, or a distance equal to approximately the width of the backing sheets. Thus in Fig. 2, the rows indicated as 2A are formed in this manner so that all tufts 3 terminate in substantially the same horizontal plane. This particular improvement can, of course, be utilized in present and conventional joining structures.

To finish the strips or the completed rug, the underside may be coated with a layer of latex which serves two purposes. First of all, it tends to bind the pile material to the backing sheet and prevents its being pulled out from the upper side; and secondly, it provides a flexible, frictional surface which tends to keep the rug from slipping.

From the above, it is obvious that the invention provides a looped pile rug which is exceedingly easy to manufacture and eliminates, to a large extent, the unsightliness of the joints, even after long use. It provides an inexpensive way of joining strips to form rugs of any desired width, by using any desired number of strips. The extra marginal edge can, of course, be cut off as desired to finish the completed rug.

I claim:

1. A rug comprising: a pair of parallel strips of backing sheet material; a plurality of rows of looped pile secured to and extending outwardly from the surface of said pair of strips excepting a marginal surface portion on one of said strips, the other of said strips being positioned in overlapping relation on said marginal portion on said one of said strips; means securing said pair of strips together in such relation along said portion, said rows of pile on the other of said strips and overlying said marginal portion being shorter than the remaining rows of pile by a distance substantially equal to the thickness of one of said strips.

2. A rug comprising: a plurality of parallel strips of uniform width of backing sheet material; a plurality of narrowly spaced parallel rows of looped pile extending longitudinally of each of said strips and covering substantially all of the surface thereof excepting a relatively wide marginal portion extending along one of the edges of each of said strips, adjacent ones of said strips being positioned in overlapped relation along said marginal portion with the overlapping edge positioned closely adjacent the outermost row of said pile; a latex adhesive positioned between said overlapped portions for securing said adjacent strips together in such relation along said portions, said rows of pile on each of said strips overlying said marginal portion of the adjacent strip being shorter than the remaining rows of pile by a distance substantially equal to the thickness of one of said strips.
